UNITED STATES PATENT OFFICE.

TIMOTHY FRANK KELLY, OF BOSTON, MASSACHUSETTS, ASSIGNOR, BY
MESNE ASSIGNMENTS, TO SAID TIMOTHY F. KELLY AND MICHAEL
R. GATELY, OF SAME PLACE.

CANTEEN.

SPECIFICATION forming part of Letters Patent No. 321,730, dated July 7, 1885.

Application filed March 2, 1885. (No model.)

To all whom it may concern:

Be it known that I, TIMOTHY FRANK KELLY, of Boston, in the county of Suffolk, of the Commonwealth of Massachusetts, have invented a new and useful Improvement in Canteens; and I do hereby declare the same to be described in the following specification and represented in the accompanying drawings, of which—

10. Figure 1 is a front elevation, Figs. 2 and 3 are longitudinal sections, and Fig. 4 a side view, of a canteen provided with my invention, the nature of which is defined in the claim hereinafter presented.

15. In the said drawings, A denotes a bottle or canteen, elliptical or otherwise suitably formed in its transverse section, and having below its bottom a a chamber, B, made by such bottom and an extension of the sides of the canteen 20 below it. There is projected upward from such chamber at its central part to the top of and through the canteen a chimney or tube, C, that opens through the top as well as through the bottom of the canteen. Within 25 the said chamber B, at its opposite ends, are two spring catches, D D, whose locking-projections b are extended, as shown, through holes c in the ends of the chamber. At the top of the canteen is a filling-neck, d, furnished with a screw cap or cover, e. Beneath the lower end of the canteen is a lamp, E, having its wick-tube f immediately in line with the chimney, in order that when the lamp is raised into the chamber B the said 35 wick-tube may extend within the chimney. The lamp is arranged in a cover or cap, F, adapted to fit to and receive within it the lower part of the canteen. From this cap or lamp-carrier there project upward two jaws, 40 G, that embrace the opposite sides of the canteen, and are perforated with holes g g, to receive the locking-projections b, there being in each jaw two such holes, one near its top and the other near its bottom. The lamp is for 45 the purpose of heating any liquid charge of the canteen. On a person grasping the canteen with one hand, and with the thumb and third finger of the other spanning the two locking-projections and pressing them inward, and at the same time pulling the lamp-carrier downward relatively to the canteen, the lamp will become exposed, to enable its

wick to be inflamed for heating the canteen, the smoke and gases of the flame passing upward through the chimney, and in so doing 55 heating it. The heat absorbed by the chimney will be imparted to the fluid around it. The educt of the chimney I usually have much smaller in diameter than the induct, in order for the smoke and gases escaping from the 60 wick of the lamp to be retained a suitable period within the chimney to impart to it most if not all of its heat.

A canteen as above described will be found to be useful to soldiers, sportsmen, artisans, 65 or workmen, and may be provided with the usual means of slinging it on the body of a person.

I do not claim a dinner-pail constructed as represented in the United States Patent No. 70 227,369, in which the lamp-holding catches are arranged wholly in the outer side of the article, and are of such nature as not to admit of the lamp being adjusted to different distances from the vessel over it, as is the case in my 75 canteen, in which the catches are within the lamp-holding chamber; nor do I claim a canteen constructed as represented in the German Patent No. 7,291, for 1878 and 1879, in which the lamp by its catches cannot be adjusted to more than one position with respect 80 to the vessel or reservoir over it. By having the catches within the canteen-chamber at its lower part, and having the jaws G G extending up from the lamp-carrier and provided 85 with sets of holes for engaging with the cutters, the lamp of my canteen can be adjusted to different positions with respect to the canteen, as set forth.

I claim—

The combination of the canteen provided with the chimney extending upward through it, and also with the spring-catches and their chamber in and arranged in its lower part, as described, with the lamp and its carrier having the perforated jaws to embrace the canteen, and provided with sets of holes g, to engage with the catches, all being substantially as set forth.

9c

TIMOTHY FRANK KELLY.
